UNITED STATES PATENT OFFICE

LAWRENCE E. BAER, OF ATTLEBORO, MASSACHUSETTS, ASSIGNOR TO BAER & WILDE COMPANY, OF ATTLEBORO, MASSACHUSETTS

HOLDER FOR THE POINTS OF SOFT COLLARS

Application filed September 10, 1930. Serial No. 480,832.

This invention relates to holders for the points of soft collars, and the primary object thereof is to provide a holder of this type which can be applied as an attachment to the usual soft collar holders of known manufacture or which can be permanently attached to such collar holders at the time of manufacture as may be desired.

A further object of the invention is to provide a holder of this type which in use is concealed and which permits movement of the points should same be subjected to pressure and restoration of the points to normal position upon release of the pressure.

The invention further aims to provide a device of this type which is of simple and economical construction and which can be easily and quickly applied to collar holders without modification of the latter.

In the drawing:

Figure 1 is a rear elevation of the invention applied to the soft collar, the latter shown in dotted lines.

Figure 2 is a top plan view;

Figure 3 is a section on line 3—3 of Figure 1,

Figure 4 is a top plan view of a modified form of the invention; and

Figure 5 is a section on line 5—5 of Figure 4.

In proceeding in accordance with the present invention a collar holder is shown by way of example, composed of the usual front bar 1 and rear bar 2 between the ends of which

the ends of the soft collar are gripped, as is well known and understood in the art. The present invention resides in the provision of a clip 3 having jaws 4 and 5 which latter are designed to be clampingly engaged with the

central portion of the collar holder. The ends of the back of the clip 3 are extended outwardly and are bent into substantially closed form so as to provide a pair of eyes 6.

A substantially inverted U shaped spring

portions of which are bent into substantially circular formation or rings 8 while the terminals 9 are sharpened so as to readily penetrate the long points of the soft collar and are offset from the plane of the circular portions 50 and extend substantially diametrically thereof, terminating within the central portions so that the latter act to protect the sharpened points as is obvious.

The member 10 is provided with a substantially U-shaped configuration at the center of the top, the ends 11 of which are received within the eyes.

From the foregoing it will be seen that the device can be readily applied to collar holders of varying manufacture as an attachment or may be permanently secured.

It will further be seen that the invention occupies a concealed relation to the collar points, and at the same time holds same in position while still permitting movement of the points due to the spring nature of the wire, and return of the points to normal position upon release of any pressure of the points which cause same to deviate from their 70 normal position.

In the modified form of the invention shown in Figures 4 and 5 the central portion 14 of the spring wire 15 is disposed within and secured by the usual binding clip 16 of 75 the front and rear bars 17 and 18 of the collar holder, whereby the spring wire is permanently attached to the collar holder at the time of manufacture of the latter.

Having thus described my invention what 80 I claim as new and desire to secure by Letters Patent is:

1. In combination with a soft collar holder, a clip formed for clamping engagement with the holder and having eyes at its ends, 85 a spring wire of inverted and substantially U-shape having its legs formed into ring shape and its terminals sharpened to provide points which latter are disposed offset from the rings and lie within the latter, the top 90

of the U-wire having a substantially U-shaped central portion the ends of which latter are engaged within the respective eyes.

2. In combination with a soft collar holder, 5 a clip formed for clamping engagement with the holder, a spring wire of inverted substantially U-shape having collar point engaging prongs on the ends of its legs and means to secure the central part of the top of the wire 10 to the clip.

3. In combination with a soft collar holder, a clip formed for clamping engagement with the holder, a spring wire having parts to engage and hold each of the points of the collar 15 in position, and means to secure the wire to the clip.

4. In combination with a soft collar holder having means to engage each of the collar ends at the upper part of the collar, a pair of 20 spring wire members independent of said first named means and having means to engage and hold the collar points in position, and means to secure said members to the collar holder.

5. In combination with a soft collar holder, a pair of spring wire members having substantially circular open parts and pointed terminals extending toward the centers of the open parts to engage and hold the collar 25 points in position, and means to secure the members to the collar holder.

6. In combination with a soft collar holder having means to engage each of the collar ends at the upper part of the collar, an inverted U-wire independent of said first 35 named means and having its ends bent into open collar engaging parts and provided with prongs, and means to secure the wire to the collar holder in depending relation there- 40 to.

7. In combination with a soft collar holder having means to engage each of the collar ends at the upper part of the collar, a clamp to engage the holder, and means carried by 45 the clamp to engage and hold each of the collar points in position.

8. In combination with a collar holder having front and rear bars, and a clip for binding same together at their centers, a collar point engaging wire received in and held 50 by the clip in position.

9. In combination with a relatively stiff collar holder having means removably and directly engageable with each of the ends of 55 the collar at the upper portion of the collar, means independent of said first named means and carried by said collar holder and projecting downwardly therefrom and formed to engage each of the collar points.

10. In combination with a collar holder having front and rear spring bars and means 60 to connect said bars whereby the same will grip and hold the ends of the collar there- 65 between at the upper portion of the collar, means carried by said connecting means and

depending therefrom and formed to engage each of the collar points.

11. In devices for holding the wings of a turndown collar in place, a member including arms and piercing points on said arms 70 for engagement with said wings and said member including clamping jaws for engaging said wings.

In testimony whereof I have signed my name to this specification.

LAWRENCE E. BAER.
